UNITED STATES PATENT OFFICE.

JAMES V. CROWTHERS, OF PHILADELPHIA, PENNSYLVANIA.

AEROPLANE.

1,098,098.

Specification of Letters Patent.

Patented May 26, 1914.

Application filed January 10, 1912. Serial No. 670,429.

To all whom it may concern:

Be it known that I, JAMES V. CROWTHERS, a subject of the King of England, and a resident of Germantown, city and county of 5 Philadelphia, State of Pennsylvania, have invented an Improvement in Aeroplanes, of which the following is a specification.

It is the object of this invention to automatically control the movement of a warping plane, aileron or other movable portion, whenever the plane or planes tilt or deviate appreciably from the horizontal, so as to automatically restore the plane to the horizontal position and prevent overturning. 10 This result I accomplish by means of a suspended gravity controlled weight, which is connected with the ailerons, flexible end or ends of the plane or planes or other movable portion and acts as an equilibrator to 15 warp the movable portion or portions when the plane is tilted so that the wind pressure acting on the warped ends or portions will tend to restore the equilibrium.

In my preferred construction the equilibrator consists of a weight, suspended from the machine at the center of gravity between the motor and the aviator's seat, and adapted to be raised and lowered, so that it may be lifted up above the running 20 gear, when the machine is at rest or about to alight, and may be lowered into operative position when the machine is in flight.

The invention may be applied either to a biplane or to a monoplane without material 25 modification and I have shown and will hereinafter describe both applications.

In the drawings: Figure 1 is a front elevation of a biplane embodying the invention; Figs. 2 and 3 are views of details 30 partly in section; Fig. 4 is a side elevation of the biplane shown in Fig. 1; Fig. 5 is a side elevation enlarged of the devices for raising and lowering the equilibrator; Fig. 45 6 is an end view of the same partly in vertical section; Fig. 7 is a front elevation of a monoplane embodying the invention; Fig. 8 is a side elevation of the same; Figs. 9 and 10 are respectively a front elevation and side elevation of a biplane showing the invention applied to the control of the 50 ailerons.

Referring first to the embodiment of the invention in a biplane as shown in Figs. 1-4: *a* is the usual frame having the motor *b* and fan *c* at the front and carrying the

aviator's seat *d*. *e*, *e*, are the two planes carried by the usual frame work *f* connected with the main frame *a*. The outer ends of the planes *e*, *e*, which are connected to one another by the rods *f'* are flexible, and free to warp or bend in unison. Suspended from the frame of the machine, preferably at the center of gravity between the seat and motor, is a weight *g*, which may be raised and lowered by suitable means. This 60 weight is connected laterally by collapsible connections *h*, *h*, with the flexible extremities of the planes *e*, *e*. It is also connected in a similar manner with the tail frame by a connection *j*. As shown the collapsible 65 connections *h*, *h*, consist of rods *h'* and *h*² connected respectively with the weight *g* and with the flexible end of the plane *e*, and provided on their inner ends with eyes *h*³ and *h*⁴ respectively. The rod *h'* passes 70 through the eye *h*⁴ of the rod *h*², and the rod *h*² passes through the eye *h*³ of the rod *h'* thus forming a sliding connection. *h*⁵ is a spring between the eye *h*³ of the rod *h'* and the outer or connected end of the rod *h*². When the planes *e*, *e*, are in horizontal 75 position, the suspended weight *g* will hang vertically and exert equal tension on the connection *h*, *h*. The rods *h'*, *h*² will then occupy the position shown in Fig. 2 with the heads *h*³, *h*⁴ in contact, and the springs *h*⁵ acting to keep them in that position. When the planes *e* assume a position out of the horizontal, the weight *g* being controlled 80 by gravity will swing to one side or the other of the vertical to the planes, as indicated in dotted lines in Fig. 1. This will cause the weight *g* to pull upon the connection *h* on one side and to push upon the connection on the other side. As the heads *h*³, *h*⁴ are in contact the pull executed by the weight *g* upon the rod *h'* will exert a direct 85 pull upon the rod *h*² thus warping or pulling down the outer ends of the planes *e*, *e* at that end. At the same time the push exerted by the rod *h'* on the other side will cause that rod to slide up on the rod *h*² putting the spring *h*⁵ under compression, and allowing the ends of the planes at that side 90 to bend or warp upward. Ordinarily, however, the tension on the spring *h*⁵ would not be sufficient for the purpose, and as it is desirable that the planes at one end should be warped upward to the same extent that they 95 are warped downward at the other end, I 100 105 110

employ a connection between the two outer ends of the plane, so that the positive downward movement at one end produced by the direct pull of the weight will produce a 5 positive upward movement at the other end. For this purpose I employ a cord *k* connected at one end with the lower front corner of the lower plane *e*, extending upward and across to a pulley *m* at the rear of the 10 end of the upper plane, thence horizontally along the upper plane to a similar pulley at the other end, and then down and across to the lower corresponding front corner of the lower plane. It follows that when the 15 ends of the plane are warped down at one end, the pull exerted by the cord *k* will positively warp up the planes at the other end. The weight *g* with its connections thus acts as an equilibrator to automatically warp 20 the planes at their ends whenever there is any change from a horizontal position, and this warping will act to restore the horizontal position and to keep the aeroplane steady. The connection *j* between the 25 equilibrator and the tail-frame may be constructed in a manner similar to the lateral connections *h*, *h*. It is intended to prevent the equilibrator from swinging longitudinally. 30 The equilibrator may be raised and lowered so that it may be drawn up out of action when the machine is at rest or alighting, and may be lowered as soon as the machine has ascended. For this purpose I 35 have shown the weight *g* provided with a rod *n* sliding in a tube *o* secured to the frame *a* and connected by a wire *p* with a winding wheel *q*, adjacent to the aviator's seat. The wheel *q* is provided with a gear *q'* 40 engaging a gear *r*, the shaft *r'* of which extends through the casing *r''* and is provided with a handle *r'''*. *s* is a ratchet clutch between the handle *r'''* and the casing *r''* which is controlled by a spring-pin *t* extending 45 through the handle. When the aviator wishes to lower the equilibrator he depresses the pin *t* to throw out the clutch and then turns the handle *r'''* to operate the wheels *r* and *q* and unwind the cable *k*. 50 The application of the invention to a monoplane, as shown in Figs. 7 and 8 is in all respects similar to the application to a biplane, except that in this case, as there is but a single plane to warp, the ends of the 55 plane *e'* are connected by a wire *k'* which runs over guides *m'* in a stationary frame *a'*, which is slightly bent up at its ends as shown at *a''* to permit the upward warping. 60 While I prefer the connections shown between the equilibrator and the ends of the plane or planes, and the means for raising and lowering the equilibrator, and also the means for connecting the opposite ends of the plane I do not mean to limit myself 65 to such devices, except where they are spe-

cifically included in the claims, as other means may be employed for the purpose without departing from the invention.

In Figs. 9 and 10 the invention is shown applied to the control of the ailerons *e²* of a machine having rigid planes. In this case the connections *h*, *h* are each connected by a wire *h⁶* with a rocker arm *t'* on the end of the plane and the arms of this rocker arm on opposite sides of the pivot are connected 70 by wires *h²*, *h²* with the opposite sides of the aileron. When a pull is exerted on the connection *h* on one side by the weight *g* it will act through the wire *h⁶* and the rocker arm *t'* to deflect the aileron on that 75 side, while the aileron at the other end will be brought back into horizontal position by the action of the wind, the tension on the connection on that side being released. 80

What I claim is as follows:

1. In an aeroplane, the combination with 85 a plane having flexible ends, of a suspended gravity controlled weight, and collapsible connections between said weight and the ends of the plane adapted to automatically warp said ends by the lateral movement of the weight with reference thereto when the connections are extended, and means to raise and lower the weight to place it into and out of operation, at the same time collapsing 90 the connections with the ends of the plane.

2. In an aeroplane, the combination of the frame provided with the motor, aviator's seat and a plane having flexible ends, a gravity controlled weight suspended below 100 the plane at substantially the center of gravity between the motor and aviator's seat, and collapsible connections between said weight and the ends of the plane adapted to automatically warp said ends by the 105 lateral movement of the weight with reference thereto when the connections are extended by the lowering of the weight.

3. In an aeroplane, the combination of the frame provided with the motor, aviator's 110 seat and a plane having flexible ends, a gravity controlled weight suspended below the plane at substantially the center of gravity between the motor and aviator's seat, and connections between said weight 115 and the ends of the plane adapted to automatically warp said ends by the lateral movement of the weight with reference thereto, and hand controlled devices adjacent to the seat for raising and lowering said weight, the connections collapsing as 120 the weight is raised.

4. In an aeroplane, the combination with a plane having flexible ends, of a suspended gravity controlled weight, and connections 125 between said weight and the ends of the plane, said connections being composed of sections free to collapse but held against extension beyond their normal position.

5. In an aeroplane, the combination with 130

a plane having flexible ends, of a suspended gravity controlled weight, and connections between said weight and the ends of the plane, said connections being composed of 5 sections free to collapse but held against extension beyond their normal position, and springs tending to hold said sections in normal extended condition.

6. In an areoplane, the combination with 10 a plane having flexible ends, of a suspended gravity controlled weight, and connections between said weight and the ends of the plane, said connections being composed of sections free to collapse but held against extension beyond their normal position, and 15 a tractive connection between the flexible ends of the plane.

7. In an aeroplane, the combination with 20 the frame, of a plane carried thereby and having flexible ends, a suspended gravity controlled weight, means to raise and lower the weight to place it into and out of action, collapsible connections between said weight and the ends of the plane adapted 25 to automatically warp the ends by the lateral movement of the weight with reference thereto when the weight is lowered and the connections are extended, and a collapsible but not extensible connection between said 30 weight and the tail of the frame.

8. In an areoplane, the combination of a

plane having a flexible end, a suspended weight movable laterally under the action of gravity, and a connection between the weight and the flexible end of the plane collapsible in the direction in which the weight swings but non-extensible in the other direction. 35

9. In an aeroplane, the combination of the frame with its plane or planes, a movable 40 portion carried thereby, and a suspended gravity controlled weight, a collapsible but non-extensible connection between said movable portion and weight adapted to move said movable portion when said weight 45 moves laterally with reference to said frame and its plane, and means to raise and lower said weight.

10. In an aeroplane, the combination of the frame with its plane or planes, a movable 50 portion carried thereby, a suspended weight arranged to move laterally under the action of gravity and a connection between the weight and movable portion collapsible in the direction in which the weight swings 55 but non-extensible in the other direction.

In testimony of which invention, I hereunto set my hand.

JAS. V. CROWTHERS.
